UNITED STATES PATENT OFFICE.

ARTHUR TREVOR DAWSON AND GEORGE THOMAS BUCKHAM, OF WESTMINSTER, LONDON, ENGLAND, ASSIGNEES TO VICKERS LIMITED, OF WESTMINSTER, ENGLAND.

CARTRIDGE-FEED MECHANISM OF AUTOMATIC GUNS.

1,091,640.

Specification of Letters Patent. Patented Mar. 31, 1914.

Application filed September 4, 1912. Serial No. 718,469.

To all whom it may concern:

Be it known that we, ARTHUR TREVOR DAWSON, knight, and GEORGE THOMAS BUCKHAM, both subjects of the King of Great Britain, residing at Vickers House, Broadway, Westminster, in the county of London, England, have invented certain new and useful Improvements in or Relating to the Cartridge-Feed Mechanism of Automatic

10 Guns, of which the following is a specification.

This invention relates to cartridge feed mechanism of the kind in which the top and bottom levers are made integral with the

15 pivot pin and in which the feed box is provided with a movable bearing piece or slide in order to permit the said integral levers and pivot pin to be placed in position in the feed box and to be removed therefrom when

20 desired.

According to the present invention the movable bearing piece or slide is in the form of a cap having a semi-circular recess and is mounted in vertical guides on the feed box 25 so that the pivot pin is completely surrounded by bearing surfaces constituted by the said recess in the bearing cap and a similar recess in the feed box. The said cap is formed with a flange adapted to co-operate 30 with a flange moving with the top and bottom levers, the said flanges being so arranged as to permit of the angular movements of the levers during the recoil and forward movements of the barrel.

35 In order that the said invention may be clearly understood and readily carried into effect we will describe the same more fully with reference to the accompanying drawings, in which:—

40 Figure 1 is a plan of the feed box showing the parts in the position they assume when the barrel is in the forward or normal position, the aforesaid movable bearing cap being removed. Fig. 2 is a view similar to

45 Fig. 1 showing the parts in the position they assume when the barrel is in the recoiled position the aforesaid movable bearing cap being in place. Fig. 3 is an end elevation of the feed box with the bearing

50 cap and the integral levers and pivot pin removed. Fig. 4 is a fragmental plan of Fig. 3. Figs. 5, 6 and 7 are respectively a side elevation, a plan viewed from beneath and an end elevation of the integral levers and

55 pivot pin. Figs. 8, 9 and 10 are respectively an end elevation, a side elevation and a plan of the movable bearing cap, and Fig. 11 is a view of a detail hereinafter referred to.

In all these figures, A is the feed box and A' the reciprocating slide or plate. 60

B is the top lever having a projection b that engages in a hole in the slide or plate A'.

B' is the bottom lever having a projection b' that engages in a slot in one of the 65 recoil plates. B² is the pivot pin connecting the said levers and made integral therewith, and C is the movable bearing cap.

B^x is the flange moving with the top and bottom levers, and C^x is the flange on the 70 movable bearing cap.

In the example illustrated, the top lever B is formed with the flange B^x the shoulders of which are diametrically opposite and are adapted to engage with the radial shoulders 75 of the flange C^x on the aforesaid movable bearing C, the latter flange being in the form of an arc which, as shown in Figs. 2 and 10, is less than a semi-circle in order to provide a space or gap to allow for the angular displacement of the levers B, B', during the recoil and forward movements of the barrel. The pivot pin B² is formed with an axial hole b² for the reception of a split retaining pin D (Fig. 11) the head d^x of which engages in a recess b^x in the top lever B and in a similar recess c^x in the top of the movable bearing cap C, the said pin D by the engagement of its enlarged end d^o with shoulders b^o in the hole b², serving to normally 80 retain the bearing cap C in position. 85

The movable bearing cap C is semi-circular in cross section as is seen from Fig. 10 and is formed with lateral fins c which engage in corresponding vertical guides a 59 (Figs. 1, 3 and 4) in the feed box A, when the bearing is being inserted or removed. The bearings for the said pivot pin B² are constituted by a semi-circular recess c^{xx} in the movable bearing cap and a similar recess a^{xx} in the feed box. 100

In assembling the integral top and bottom levers, the reciprocating slide A' is retained by hand in approximately the position shown in Fig. 1, and the pivot pin B² is inserted in the semi-circular recess a^{xx} with the projection b on the top lever B in engagement with its hole in the slide A'. The 105

levers are then moved until the slide is in the position shown in Fig. 2 and the movable bearing cap C is slid into place in the feed box as aforesaid; the split retaining pin D is then inserted and the parts are in the working condition. In removing the parts the above described operations are reversed.

What we claim and desire to secure by Letters Patent of the United States is:—

- 10 1. In cartridge feed mechanism for automatic guns, the combination of a feed box having a semi-circular recess, a pivot pin disposed in said recess, top and bottom levers rigidly connected to said pivot pin, and a semi-circular bearing cap for said pivot pin, slidably mounted in said feed box in the direction of the axis of said pivot pin, said pin being completely surrounded by the recess and bearing cap.
- 15 2. In cartridge feed mechanism for automatic guns, the combination of a feed box having a semi-circular recess, a pivot pin disposed in said recess, top and bottom levers made integral with said pivot pin, and a semi-circular bearing cap for said pivot pin, slidably mounted in said feed box in the direction of the axis of said pivot pin, said pin being completely surrounded by the recess and bearing cap.
- 20 3. In cartridge feed mechanism for automatic guns, the combination of a feed box having a semi-circular recess, a vertically arranged pivot pin disposed in said recess, top and bottom levers made integral with said pivot pin, and a vertically sliding semi-circular bearing cap for said pivot pin, said pin being completely surrounded by the recess and bearing cap.
- 25 4. In cartridge feed mechanism for automatic guns, the combination of a feed box having a semi-circular recess, a pivot pin disposed in said recess, top and bottom levers rigidly connected to said pivot pin, a flange on said top lever, a semi-circular bearing cap for said pivot pin, slidably mounted in said feed box in the direction of the axis of said pivot pin, said pin being completely surrounded by the recess and bearing cap, and a flange on said bearing cap.
- 30 5. In cartridge feed mechanism for automatic guns, the combination of a feed box having a semi-circular recess, a vertically arranged pivot pin disposed in said recess, top and bottom levers made integral with said pivot pin, and a vertically sliding bearing cap for said pivot pin, said pin being completely surrounded by the recess and bearing cap.

top and bottom levers made integral with 55 said pivot pin, a flange on said top lever, a vertically sliding semi-circular bearing cap for said pivot pin, said pin being completely surrounded by the recess and bearing cap, and a flange on the upper end of said bearing cap.

6. In cartridge feed mechanism for automatic guns, the combination of a feed box, a pivot pin, top and bottom levers rigidly connected to said pivot pin, a bearing cap for said pivot pin, slidably mounted in said feed box in the direction of the axis of said pivot pin, a retaining device passing through the said pivot pin, and means forming part of said device for coöperating with 60 said bearing cap and pivot pin.

7. In cartridge feed mechanism for automatic guns, the combination of a feed box, a vertically arranged pivot pin, top and bottom levers made integral with said pivot 75 pin, a vertically sliding bearing cap for said pivot pin, a spring retaining pin passing through an axial hole in said pivot pin for coöperating with the bearing cap and pivot pin.

8. In cartridge feed mechanism for automatic guns, the combination of a feed box, a vertically arranged pivot pin, top and bottom levers made integral with said pivot pin, a flange on said top lever, a flange on 85 the upper end of said bearing cap, a vertically sliding bearing cap for said pivot pin, a spring retaining pin passing through an axial hole in said pivot pin for coöperating with the bearing cap and pivot pin.

9. In cartridge feed mechanism for automatic guns, the combination of a feed box, a vertically arranged pivot pin, top and bottom levers made integral with said pivot pin, a semi-circular flange on said top lever, 95 a flange smaller than a semi-circle on the upper end of said bearing cap, a vertically sliding bearing cap for said pivot pin, a spring retaining pin passing through an axial hole in said pivot pin for coöperating 100 with the bearing cap and pivot pin.

In testimony whereof we affix our signatures in presence of two witnesses.

ARTHUR TREVOR DAWSON.
GEORGE THOMAS BUCKHAM.
